UNITED STATES PATENT OFFICE.

SIDNEY C. HILLS, OF TORRINGTON, CONNECTICUT, ASSIGNOR TO THE TURNER & SEYMOUR MANUFACTURING COMPANY, OF TORRINGTON, CONNECTICUT, A CORPORATION OF CONNECTICUT.

SASH-CURTAIN FIXTURE.

Application filed April 28, 1921. Serial No. 465,172.

To all whom it may concern:

Be it known that I, SIDNEY C. HILLS, a citizen of the United States, residing at Torrington, county of Litchfield, State of Connecticut, have invented certain new and useful Improvements in Sash-Curtain Fixtures, of which the following is a full, clear, and exact description.

My invention relates to improvements in curtain fixtures, and has for its object to provide a simple and mechanically efficient straight curtain rod of the flat type and end brackets such that the flat rod will be securely held in place and held from turning about its longitudinal axis.

The following is a description of an embodiment of my invention, reference being had to the accompanying drawings in which:

Fig. 1 shows a plan view of the fixture secured to the face of a window frame;

Fig. 2 shows a side elevation of the same on an enlarged scale;

Fig. 3 shows a horizontal sectional view on the line 3—3', Fig. 2; and

Fig. 4 shows a fixture mounted with the brackets secured to the opposing faces of the frame.

Referring more particularly to the drawings, 1 is the frame of a window having the sash 2. 3—3' are sections of a flat telescoping rod, the vertical dimension being much greater than the horizontal dimension. These sections have on their rear faces approaching flanges forming sockets. 4—4' are keepers secured to the frame and supporting curved loops 5—5' pivotally mounted therein, the pivotal portions of the loops being closed and the opposite ends thereof being open as shown at 6, the sides of said loops being parallel so as to make a snug engagement with the opposing interior walls of the sockets at the outer ends of the sections 3—3' respectively. The free ends of the loops are turned inwardly so as to approach one another and aid in the insertion of the loops in the ends of the sections. The loops are curved about a vertical axis adjacent to their pivotal points so as to space the rod from the face of a frame.

As shown in Figs. 1-3, the keepers 4 can

be mounted upon the outer face of the sash or can be mounted upon the inner faces 7 thereof.

In mounting the fixture, the keepers are first secured in the desired position and the 55 rod is then put into place, the telescoping section being pulled out sufficiently to slip over the yielding arms of the loop 5. The fixture thus provided when thus assembled is well supported and is simple to manufac- 60 ture and neat in appearance.

When one end of the telescoping body portion is disengaged from its bracket the remainder is supported so that it together with the curtain can be swung inward away from 65 the window.

As will be evident to those skilled in the art, my invention permits of various modifications without departing from the spirit thereof or the scope of the appended claims. 70

What I claim is:

1. In a curtain fixture, the combination of a rod comprising two vertically flattened telescoping sections and two brackets each composed of a keeper and an elongated loop pivotally mounted therein to turn about a substantially vertical axis, the arms of said loops terminating in free ends and lying in a vertical plane and entering ends of said sections. 75

2. In a curtain fixture, the combination of a rod comprising two vertically flattened telescoping sections and two brackets each composed of a keeper and an elongated loop pivotally mounted therein to turn about a substantially vertical axis, the arms of said loops terminating in free ends and lying in a vertical plane and entering ends of said sections, the arms of said loop being curved about a vertical axis adjacent to said keepers. 80

3. In a curtain fixture, the combination of a rod comprising two vertically flattened telescoping sections and two brackets each composed of a keeper and an elongated loop pivotally mounted on the keeper to turn about a substantially vertical axis, the arms of said loop lying in a vertical plane and entering ends of said sections, the arms of said loop being curved about a vertical axis adjacent to said keepers, each of said loops 100

terminating in two free approaching ends at the portion remote from its keeper.

4. In a curtain fixture, the combination of a vertically flattened rod, a bracket for detachably securing one end of the rod in place, a bracket for the other end of the rod comprising a keeper, and a member having

a horizontal portion telescopingly engaging the rod and a vertical portion pivotally mounted in an aperture in the keeper to enable the rod to be turned about a vertical axis when detached from the first mentioned bracket. ¹⁰
